IGNITION WIRE BOOT FOR SPARK PLUGS

Richard P. Dugger, South Bend, Ind., assignor to
Ristance Wire, Inc., Bremen, Ind.

Filed June 1, 1972, Ser. No. 58,940

Term of patent 14 years

Int. Cl. D13—03

U.S. Cl. D26—1 A

Fig. 1

Fig. 2

Fig. 3

Fig. 5

Fig. 4

Fig. 6

FIG. 1 is a perspective view of an ignition wire boot for spark plugs embodying the present design;

FIG. 2 is a side elevational view of the ignition wire boot for spark plugs shown in FIG. 1;

FIG. 3 is a view of the bottom of the boot as seen in FIG. 1;

FIG. 4 is an elevational view of the side opposite that shown in FIG. 1;

FIG. 5 is an elevational view of the end of the boot shown in FIG. 1; and

FIG. 6 is an elevational view of the end opposite that shown in FIGS. 1 and 5.

I claim:

The ornamental design for an ignition wire boot for spark plugs, substantially as shown.
